US00D612948S

(12) **United States Design Patent**
Fleury et al.

(10) **Patent No.:** US D612,948 S
(45) **Date of Patent:** ** Mar. 30, 2010

(54) **LABORATORY APPARATUS**

(75) Inventors: **Antoine Fleury**, Paris (FR); **Nicolas Regentete**, Paris (FR); **Fabien Deboves**, Rueil Malmaison (FR); **Axel Lehouetzki**, Paris (FR); **Emmanuel Nardin**, Vanves (FR)

(73) Assignee: **Diagnostica Stago**, Asnieres (FR)

(**) Term: **14 Years**

(21) Appl. No.: **29/307,369**

(22) Filed: **Apr. 15, 2008**

(30) **Foreign Application Priority Data**

Oct. 15, 2007 (EM) 000807763

(51) **LOC (9) Cl.** **24-01**

(52) **U.S. Cl.** **D24/216; D24/232**

(57) **CLAIM**

The ornamental design of a laboratory apparatus, as shown and described.

DESCRIPTION

FIG. 1 is a front, left and top side perspective view of an embodiment of the laboratory apparatus showing the new design;

FIG. 2 is a top plan view thereof;

FIG. 3 is a front elevational view thereof;

FIG. 4 is a right side elevational view thereof; and,

FIG. 5 is a left side elevational view thereof.

The broken lines are included for the purpose of illustrating portions of the laboratory apparatus that form no part of the claimed design.

1 Claim, 5 Drawing Sheets
